UNITED STATES PATENT OFFICE.

CHRISTIAN FREDERICK AND CHARLES N. TRUMP, OF WILMINGTON, DEL.

PNEUMATIC HAMMER.

SPECIFICATION forming part of Letters Patent No. 348,837, dated September 7, 1886.

Application filed December 10, 1885. Serial No. 185,223. (No model.)

To all whom it may concern:

Be it known that we, CHRISTIAN FREDERICK and CHARLES N. TRUMP, citizens of the United States, residing at Wilmington, in the 5 county of New Castle and State of Delaware, have invented certain new and useful Improvements in Pneumatic Hammers; and we do hereby declare the following to be a full, clear, and exact description of the invention, such as will 10 enable others skilled in the art to which it appertains to make and use the same, reference being had to the accompanying drawings.

The object of our invention is to provide an improved percussion-tool or pneumatic hammer, the combined hammer-piston striking a tool-holder with anvil-head either within or outside of the cylinder, the anvil being retracted to position for receiving other blows by direct hand pressure on the tool in use, or 20 by spring or other appropriate means.

The implement furnished with proper bits can be used for drilling and cutting stone, carving wood, engraving, chipping, riveting, and caulking iron, steel, and other metals, and combines in a simple compact form in one tool the 25 means for effectually performing a wide range of work. Compressed air or other elastic medium under pressure can be used as motive force.

30 In the drawings, Figures 1, 2, and 3 represent longitudinal sections of different forms of our device, and Figs. 4 and 4^a a device for regulating the force of the blow.

Like letters indicate corresponding parts in 35 all the figures.

A is the cylinder; B, the piston and hammer, to the head of which is attached a guide-rod, D, extending through cylinder-head E, and serving to reduce the effective pressure area 40 of the driving end of the piston to less than that of the reversing end. In Fig. 3 this guide-rod works through a splined thimble, U, and thus furnishes means for turning the piston in the cylinder either automatically or by hand.

45 The driving agent is admitted through inlet G. Transmission-port H and exhaust-port I are provided. The piston opening and closing these ports, valves are unnecessary, although, as shown in Figs. 2 and 3, a piston-valve is added, by means of which a supple-

mentary exhaust-port is opened and closed automatically for the purpose of relieving the advancing piston from excessive back-pressure.

The lower end of cylinder, Figs. 1 and 3, is 55 closed by head F, bored out to receive tool-holder C L, the anvil-head C being within the cylinder. In Fig. 2 the piston is provided with elongated hammer end e, which passes through head F, and strikes the anvil-headed 60 tool-holder carried in external case, R; or the end e may be still farther extended, and having properly-constructed bits attached, and the guide-rod D furnished with spiral groove and ratchet-thimble (or other suitable device) 65 for turning the piston automatically during the reverse movement. The implement may be used for drilling rock.

The tool-holder C L is provided with chuck or equivalent mechanism for holding the bit 70 or tool to be used, its enlarged head or anvil C fitting the case S. After receiving a blow from the hammer the anvil is retracted to position for receiving other blows by a spring coiled around the body of tool-holder by compressed air admitted to case S through small 75 port X, connecting it with cylinder A, or by direct pressure of the hand on the bit in use. A wide keyway is cut longitudinally through the tool-holder and casing, (shown in cross-section in Fig. 1, and side view in Fig. 3,) and a narrow key, M, inserted under a cam-ring N, having spirally-inclined edges, with which the ends of the key projecting beyond the casing engage. This device is shown in 80 detail in Figs. 4 and 4^a. By turning ring N and confining it when properly placed by a thumb set-screw the anvil may be drawn more or less away from the blows of the hammer and the force of the blow regulated at 85 will. A collar, Q, as shown in Fig. 2, screwed on over the casing and engaging with a collar, V, on projecting shank of tool-holder, may be used for the same purpose.

Inlet G, Fig. 1, is furnished with a cock for 90 regulating the supply of air. To guard against the piston stopping in position to close both transmission and exhaust ports, a supplementary passage, f, Fig. 1, is provided, leading from the air-supply to transmission passage, the 95

key of the cock having a second air-port, so that as the key is turned air passes to the hammer end of the cylinder, forcing the piston back, so as to uncover the exhaust-port before 5 air is admitted to the driving end of the piston through the main opening in the key.

Exhaust-port I should open into a tube, y, so placed as to direct the escaping air upon the work to remove dust. A series of exhaust-ports, as 1 2 3, may be made and covered with a sliding piece or a second tube fitted inside of y, through which openings are made corresponding to exhaust-ports 1, 2, and 3, so that when the inner tube is turned by a 15 key either one of the exhaust-ports shall communicate with the directing-tube, and exhaust takes place when the piston on its reverse movement passes the port which is open.

Piston B, Fig. 3, has slots or recesses T T' T" 20 cut in its surface, terminating at different distances from its upper end. By means of splined thimble U, through which guide-stem D works, the piston may be turned so that either of the slots will, in connection with the walls of the 25 cylinder, form a connecting-passage between ports H and p at the termination of the reverse movement.

Piston-valve a, Fig. 3, is a reduced copy of B, Fig. 1, in that its two surfaces are of unequal area. The chamber in which it works is 30 connected with main cylinder by small ports o and p. The valve is connected with tubular valve b, actuating it to open and close relief-port i.

35 When valve a is used, the two-way cock is not required and exhaust I is not essential, though advantageous when working the hammer full stroke, or when a groove is turned in the surface of piston in place of slot T, as indicated by dotted lines, and when the device is used as a rock-drill.

A suitable bit or chisel being fastened in the tool-holder and the implement placed in position by the operator using compressed air for 45 motor, the action is as follows: As the key of the cock is turned to admit the driving agent a puff at full pressure passes through the smaller opening in it to the hammer end of the cylinder, insuring the proper position of the 50 piston for starting. The opening movement of the key being continued the air admitted drives piston B forward, causing the hammer-face to strike anvil C. Port H being uncovered, compressed air is transmitted to the lower 55 end of the cylinder, and, acting upon the larger area of the hammer end of the piston, reverses the movement. When exhaust-port I is uncovered, the partially-expanded medium escapes and the piston is again driven forward. 60 Valve a, Fig. 3, in action opens relief-port i, allowing air to escape from the cylinder in front of the advancing piston. Air at full pressure entering the small chamber above the valve forces it forward, carrying with it

tube b and uncovering relief-port i. When 65 the upper end of B passes port p, air at full pressure enters the chamber under valve a, and by reason of the greater area of that end of the valve forces it back, closing relief-port i, thus confining the air requisite 70 to cushion the piston. While still moving forward, as described above, the blow is delivered, and port H being simultaneously uncovered the movement of the piston is reversed. When the upper end of slot T passes 75 p, communication is open between valve-chamber and lower end of cylinder, and the air in that being partially expanded or at normal pressure by reason of the opening of exhaust-port I, valve a is again driven forward and the 80 movement of the hammer-piston repeated.

We are aware that cylinders without valves of the form herein described have been used for rock-drilling, and we do not broadly claim such forms; but,

Having described our invention, what we do claim, and desire to secure by Letters Patent, is—

1. In a pneumatic hammer, a cylinder of uniform diameter with transmission and exhaust ports, a hammer-piston fitted to the cylinder and adapted to control the valves, with extension-rod D passing through cylinder-head, serving to reduce the effective area of driving end of piston, in combination with 90 anvil-headed tool-holder or tool carried in case formed in cylinder-head next hammer end of piston or attached thereto, substantially as described.

2. In a pneumatic hammer or percussion-tool, the combination, with chamber or chambers provided with transmission and exhaust ports and piston fitting thereto, of an auxiliary valve-chamber, and communicating ports o p, piston-valve a, tube-valve b, connected 100 thereto, relief-port i, and recess or slots in surface of piston forming connecting passages between p and H when reverse movement of piston is completed, substantially as described.

3. In a pneumatic hammer, an anvil-headed 110 tool holder and case in which it reciprocates, a port connecting the case with the main hammer-cylinder to admit compressed air below the anvil-head on the reverse movement of the hammer, so as to assist in retracting the 115 anvil into position for receiving blows from the hammer, substantially as described.

4. In a pneumatic hammer, the combination of tool-holder provided with wide longitudinal keyway, a narrow key, and a spiral-edged 120 cam-adjusting ring engaging the ends of the key, whereby the force of the blow may be regulated, substantially as described.

5. In a pneumatic hammer, a series of exhaust-ports covered by a slide or slides or 125 opening into a tube, provided with an inner tube movable therein and having openings corresponding with each of the exhaust-ports,

so that when the slide or tube is set exhaust may occur through either of the ports, as may be desired, substantially as described.

6. In a pneumatic hammer, the combination of the cylinder, transmission port, and two-way cock adapted to admit the driving agent to the hammer end of cylinder, so as to complete the reverse movement of the piston before air is admitted to the driving end, substantially as described.

In testimony whereof we affix our signatures in presence of two witnesses.

CHRISTIAN FREDERICK.
CHARLES N. TRUMP.
